WITNESS:

Robert R. Winter
INVENTOR
BY Victor J. Evans
ATTORNEY

UNITED STATES PATENT OFFICE.

ROBERT REX WINTER, OF LELAND, MISSISSIPPI.

FAN ATTACHMENT.

Application filed April 18, 1922. Serial No. 554,523.

To all whom it may concern:

Be it known that I, ROBERT R. WINTER, a citizen of the United States, residing at Leland, in the county of Washington and State of Mississippi, have invented new and useful Improvements in Fan Attachments, of which the following is a specification.

The object of this invention is to provide for distributing the air current from an electric fan in a more satisfactory manner than is possible under usual conditions.

A further object is to provide a device of this type which may be sold at a very reasonable figure, and one which will also serve as a guard member, or additional guard member.

A further object is to provide a device designed to take the place of an oscillating attachment, and a device which will distribute the air currents over a greater area and thereby lessen the inconvenience arising from a strong direct breeze, because of its tendency to displace all light articles in its path, and because of the injurious effects sometimes produced on the health of the individuals making use of the fan.

A still further object is to provide particular means for effecting connection with the usual wire guard.

With the foregoing and other objects in view, the invention consists in the novel construction and arrangement of elements described and claimed, it being understood that modifications may be made within the scope of the claims without departing from the spirit of the invention.

In the drawings, Figure 1 is a view of the device in front elevation, as applied to a fan; Figure 2 shows the fan structure in top plan, and the attachment in horizontal section; Figure 3 is a front elevation of an attachment employing blades or vanes extending in two directions; Figure 4 is a detail view showing how the blades may be connected with the annular member.

The annular element 10 may be provided with an outwardly extending flange 11 and

with a portion 12 providing an annular groove 13 designed to cooperate with the usual guard carried by an electric fan. 50

Various types of securing devices may be employed, depending upon the wishes of the manufacturer, but in the drawings I have shown the securing devices designated 15 and 16. 55

The blades or vanes 18 may be assembled in two series on either side of the center of the element 10. These vanes are suitably secured to member 10, as by soldering, welding or by providing tongues 20 extending through slots 21 and being outwardly deflected beyond the outer wall of member 10. 60

If desired horizontal blades 22 and 23 may be located as shown. The relative proportions of the various parts are unimportant. All of the blades may be set at the same angle, or the outer blade may have a greater inclination, as shown in the drawings. The usual fan guard is designated 25 and the fan blades are shown at 26. 70

Having thus described the invention, I claim:

1. A device of the class described, comprising an annular member, means for attaching said member to a fan structure, a plurality of vanes extending across said annular member and positioned at an angle with reference to the path of a current of air from the fan, and blades extending transversely with reference to the vanes. 75 80

2. A device of the class described, comprising an annular member provided with an annular groove for cooperation with a guard member of a fan, securing devices for the annular member, and a plurality of vanes extending across the annular member, said vanes being arranged in two series and the outer vanes being at a greater angle with reference to the normal path of the air currents than the remaining vanes, and air deflecting members extending transversely of some of said vanes. 85 90

In testimony whereof I affix my signature.

ROBERT REX WINTER.
